UNITED STATES PATENT OFFICE.

ALVA J. FISHER, OF EVANSTON, ILLINOIS, ASSIGNOR TO HURLEY MACHINE COMPANY, OF CHICAGO, ILLINOIS, A CORPORATION OF ILLINOIS.

WASHING MACHINE.

Application filed October 7, 1921. Serial No. 505,977.

To all whom it may concern:

Be it known that I, ALVA J. FISHER, a citizen of the United States, residing at Evanston, in the county of Cook and State 5 of Illinois, have invented certain new and useful Improvements in Washing Machines, of which the following is a specification.

This invention relates to laundry washing machines and more particularly to the 10 rotating drum or container for tumbling or agitating the laundry, and the main object of the invention is to construct the drum or container of metal stampings and parts which are quickly and easily assembled and 15 cheaply manufactured, while at the same time the drum combines and embodies the advantages of light weight, great strength, simplicity, maximum efficiency, minimum wear and tear on the laundry, avoidance or 20 prevention of warping, distortion, rust or corrosion of the parts and ease of repair.

With the above and incidental objects in view the invention consists in certain 25 novel features of construction and combination of parts, the essential elements whereof are recited in the appended claims and a preferred form of embodiment of which is described in detail hereafter and illustrated in full in the accompanying drawings which 30 form part of this specification.

Of said drawings, Figure 1 is a sectional view taken through a washing machine, the section being taken near the right hand end of the machine to show the rotating drum, embodying the present invention, in end 35 elevation; Fig. 2 is a cross-section through the drum, shown in Fig. 1; Figs. 3 and 4 are detailed sections taken on lines 3—3 and 4—4, respectively, of Fig. 1; Fig. 5 is a 40 longitudinal section through the drum, as on the line 5—5 of Fig. 2 and with the middle portion of the drum broken away; Fig. 6 shows full sized sections, taken on the same longitudinal line, through opposite 45 end portions of a wall section and the adjacent end portions of the heads of the drum; Fig. 7 is a transverse section through a portion of the door or cover and the parts in proximity with its rear edge, the section 50 being taken as on the line 7—7 of Fig. 5; Fig. 8 is a perspective view of the forward portion of a side plate of the door or cover; Fig. 9 is a section on the line 9—9 of Fig. 4; Fig. 10 is a section on the line 10—10 55 of Fig. 7; Fig. 11 is a perspective view of

a fragment of one of the heads, and Fig. 12 is a section on the line 12—12 of Fig. 7.

Referring to Fig. 1 of the drawings, the washing receptacle or tub 1 is preferably of the general type illustrated in my co-pending application, Serial No. 338,511, filed November 17, 1919 and comprises two metal end frames 2 and a tub consisting of a cylindrical sheet metal wall 3, ends 4, and a door or cover 5, hinged at 6 and provided with a handle 7 near its front edge to facilitate the opening and closing of the cover. The laundry tumbling or agitating drum 8, embodying the present invention, is rotated in the tub about trunnions 9 and 10 (Fig. 50) by an electric motor 16 through suitable gearing, not shown. The trunnion 9 projects from a plate 11 fastened to one end of the drum 8 and is adapted to seat in a bearing (not shown) on the corresponding 75 end 4 of the tub. The trunnion 10 projects from the other end of the tub into a bearing 12 on the plate 13 fastened to the adjacent end of the drum and is held therein by a slide 15 (Fig. 1) which is operated by 80 a lever 14 to permit removal of the drum from the tub, as is well understood in the art.

The drum 8 comprises ends or heads 17, baffles or agitators 18, a plurality of curved 85 sections 19 forming the cylindrical shell or wall, and a cover or door 20. The ends or heads 17 are formed of sheet metal discs stamped by dies to give them the required shape or contour. Stamped centrally in 90 each head 17 is a five-point star 21 having a circular center portion 22 with the points of the star forming radiating ribs, the star depressions being formed to add rigidity and strength to the heads. The inner sides 95 of the plates 11 and 13, which are riveted or otherwise fastened to the heads, conform to these depressions. Adjacent the periphery of each head is formed an annular rib 23 (Fig. 6) forming a circular groove 24 opening inwardly, and an overhanging flange 25.

The four sections 19, forming the cylindrical wall of the drum or cylinder are alike in construction and each is formed from a blank of sheet metal, being given the desired shape by means of suitable dies. These curved sections 19 and the heads 17 are preferably formed of the same thin sheet metal, which possesses considerable strength while at the same time it has rust- 100 105 110

proof and non-corrosive characteristics. The transverse edge portions of the sections are curved outwardly and then towards each other to form curved edges and over-hanging flanges 26 so that when the sections are assembled on the heads the curved edges seat firmly in the grooves 24 in the heads and the flanges 26 press against the flanges 25 to assure a tight fit between the ends 10 of the sections and the heads. The longitudinal edge portions of the sections 19 are provided with grooves 27 (Figs. 2 and 7) and the outer walls 28 of the grooves are curved cylindrically.

15 It will be observed that channels or grooves 29, somewhat V-shaped in section are on the inside of the drum in the corners formed by the union of the sections 19 with the heads 17 and contiguous with the line 20 of contact 30 of the sections with the heads. This feature, the principle of which is followed at various places throughout the drum is a very important one, its purpose being to prevent pieces of laundry, and particularly garments or fabrics of delicate or fine texture, such as laces and silks, from becoming fastened, caught or cut on sharp edges or between the contacting surfaces or edges of the sections and heads and consequently torn or damaged.

30 In the present invention the line of contact between any two surfaces or parts, such as that between the sections and a head do not contact with the laundry because the narrow channels, 35 adjacent the line of contact, such as the channels 29, keep or space the laundry away from the same.

The baffles or agitating plates 18 are preferably formed of some light but strong and 40 rigid metal, such as an aluminum alloy which is non-rusting and non-corrosive. The baffles are corrugated or ribbed lengthwise, as shown in Figs. 2 and 7, to give them added strength. The ends of the baffles are 45 of uniform thickness (transversely of the baffles) and the corrugated portions merge therewith to avoid sharp corners. These ends of the baffles are seated in equi-spaced depressions 31 (Figs. 2, 7 and 12) which are 50 formed in the heads 17. These depressions have the same depth as and merge with the grooves 24 and are widened or flared at their outer or merging ends to accommodate the ends of the grooved edge portions of the 55 sections 19, it being understood that the turned traverse end portions of the sections terminate short of the grooved edge portion, as indicated at 32 (Fig. 7). The side walls of the depressions are inclined to provide the channels or grooves 33 which prevent the laundry from probably getting fastened between the contacting edges of the baffles and heads, as explained above.

60 The inner longitudinal edge of each baffle 65 plate is provided with an integral bead 34,

substantially semi-cylindrical in cross-section, and a corresponding bead 35 is provided on the outer edge, but each bead 35 is further provided with a ledge or projecting rib 38 extending the length of the baffle plate. The baffle plates at the front and rear edges of the door or cover opening are constructed slightly differently than the other baffle plates, the ribs 38 of the former being provided with a single over-hanging flange 39 while the ribs 38 on the other baffle plates are T-shaped in section, thus providing two flanges 39. The longitudinal edges of the sections 19 project into the grooves 37 formed by the flanges 39 and the beads 35, the curved marginal portions 28 of the sections being in contact with the complementary, cylindrically-curved surfaces 41 of the beads. Channels 42 are provided between the beads and the portions 28 adjacent the line of contact to prevent any laundry from being caught or pinched or cut as explained above. As shown in Figs. 3 and 4 the flanges 25 of the heads fit in recesses or cut-away portions 36 in the ends of the ribs or ledges 38.

95 The ends of the baffles 18 are equipped with bosses 44 provided with screw threaded openings into which headless screws 45 are screwed (Figs. 3, 4, 5, 9 and 10). As shown in Fig. 9 one side of each screw is flattened and after the screw has been placed in the opening the side of the boss 44 opposite the flattened side of the screw is also flattened in any desired manner so that it will positively prevent the screw from working loose or being withdrawn from the boss. The screws project through apertures in the bases of the depressions 31 in the heads and their projecting ends carry washers 47 and 100 nuts 48, the screws, nuts, and washers being the only devices employed for fastening the heads securely to the baffle plates and holding the baffle plates, the heads and the wall sections 19 in assembled condition. The nuts 48 on the screws for the baffle plates adjacent the door opening are provided with integral sleeves or bosses 50 for purposes to be described later, it being understood 105 that the other nuts 48 are not provided with these bosses.

110 The main panel of the door or cover 20 is formed of the same kind of sheet metal as the sections 19 and is curved on the same radius to complete the cylindrical form of the drum. It is approximately of the same width (from front to rear) as each of the sections 19, but is somewhat shorter in length (from side to side) as shown in Fig. 5. The front edge of the door is rolled outwardly about the stiffening rod 53 (Fig. 2) which is as long as the main panel and the rear edge of the main panel is bent inwardly to form a flange 54 having a cylindrical portion 115 contacting with the forward semi-cylindrical portion 120

drical portion 55^a of the bead 35 of the adjacent baffle plate (Fig. 7). Riveted or otherwise secured to the transverse edges of the main panel of the door are plates 55 (Figs. 5 1, 2 and 7), preferably thicker than the main panel in order to give added strength and rigidity to the door and to serve as pivot or hinge plates. The portions of the flanges 25 (Fig. 11) on the heads within the door opening are rolled into the grooves 24 to form smooth edges and the plates 55 are provided with grooves 56 which fit over these rolled edge portions of the heads when the door is closed.

15 The sleeves or bosses 50 (Fig. 10) of the nuts 48 on the outer screws in the baffle plate at the rear edge of the door project through flared openings 57 in the rear enlarged ends of the overhanging flanges 56^a of the plates 20 55 and serve as pivots for the door. The forward ends of the flanges 56^a have circular depressions in which are secured metal discs 58 (Fig. 8) the discs and plates being provided with cut-away portions forming 25 shoulders 59 with which noses or projections 60 on latches 61 engage to lock the door in closed position (Figs. 1 and 3). The latches 61 are pivoted on the bosses 50 of the inner nuts 48 carried by the screws on the 30 baffle plate at the front edge of the door and the bosses on the outer nuts project through slots 63 in the latches, which have finger pieces 64 to facilitate their manipulation. Springs 67 at one end are coiled about the 35 bosses on the outer nuts and the opposite ends of the springs after passing under the bosses on the inner nuts press against flanges 65 to force the latches into latching position. When the door is closed the curved edges of 40 the plates 55 under the shoulder 59 engage inclined edges 66 on the latches to force the latches forwardly until the shoulders 59 and 60 are in registry when the springs move the latches into latching position, it therefore 45 being unnecessary for the operator to touch the latches while the door is being closed.

Mounted on the bosses 50 of the nuts on the baffle plate at the rear edge of the door are springs 68 having projecting bent portions 69 which contact with the rear edges 50 of the flanges 56^a of the plates 55. The springs 68 are so tensioned that, when the latches are operated to release the door, they move the door to the partially opened position shown in dash lines in Fig. 7. The door 20 may then be raised or fully opened by hand to the position represented by the dot-dash lines in Fig. 7. This is a very important feature of the invention as it requires or warns the operator to close the door of the drum tightly before the machine is operated. One serious objection to washing machines now on the market is that the door may be closed but not always latched and 60 when this condition exists and the machine is operated the laundry falls out through the opening and is torn and mutilated between the drum and tub and the drum and tub may be injured. With the present construction the operator may close the door and think that it is latched, but on removing her hand the door, if not actually latched, will spring 70 partially open, giving full warning that it was not latched in closed position.

It will be noted that when the door is closed the rear edge of its flange 54 is flush or contacts with the flat surface of the baffle plate immediately under or contiguous to the curved portion 55^a of the bead, this close fit being very desirable to avoid threads 75 of the laundry from being caught or fastened between the flange and the baffle plate. The cylindrical surface of the flange 54 is also in contact with the cylindrical surface 55^a while the door is being closed for the same purpose. When the door is fully opened it may, if desired, be resiliently retained in such position by the engagement of its flange 54 against the top edge of the rib 38 of the baffle plate, the 80 yielding character of the flange 54 being availed of to accomplish this result.

The main panel of the door and the sections 19 are provided with numerous apertures 70 (Figs. 5 and 6) which are preferably arranged in parallel longitudinal and transverse rows. The function of these holes or apertures as is well known in the art, is to permit circulation of the air and water. The metal around the holes is 85 pressed or stamped outwardly to form frusto-conical depressions 71 with the holes at the apexes and the metal at the bases of the depressions is stamped inwardly to form annular ribs 72. The metal at the edge of each hole is rolled outwardly back upon itself to form a smooth continuous rounded edge about the hole. This construction, while simple embodies very important advantages. The integral rolled edges present 90 smooth rounded surfaces bounding the holes and free from the cracks, corners, or sharp edges within the holes and on the inside of the drum and therefore cannot cut or catch the laundry.

In Fig. 10 I have shown the outer ends of the openings through the nuts 48 filled with solder or other soft metal 74, all of the nuts being preferably treated in this way 95 to prevent them from working loose. It is obvious however that this soft metal does not prevent the nuts from being readily removed by a wrench when it is desired to disassemble the drum or remove a part thereof.

From the above description it will be apparent that its drum is quickly and easily assembled and disassembled, the only fastening devices being the screws 45 and the nuts 48, as the sections 19 are held in position 100 105 110 115 120 125 130

by reason of the engagement of their transverse and longitudinal edges in the grooves 24 in the heads and the grooves 37 in the baffle plates. The heads and sections 19 are 5 formed of very thin sheet metal and, therefore, have a somewhat resilient character so that when the parts are assembled the curved or rounded transverse edge portions of the sections fit tightly and firmly in the 10 grooves 23 and the curved marginal portions 28 are firmly pressed against the complementary curved portions 41 of the beads on the baffle plates. This affords a very simple 15 and yet very rigid drum construction which prevents any torsional or twisting movement of the drum, that is to say, any relative movement between the heads, it being important to prevent such torsional movement as the drum is driven from only one head or 20 end. At the same time the drum has no parts which can become warped or distorted, and laundry of the finest texture or character is prevented from being caught or fastened between the parts by virtue of the 25 narrow channels or grooves formed adjacent the lines of contact of the parts. The edges around the holes 71 are smooth and rounded, presenting no crack or sharp edge which might catch or cut the laundry and 30 the metal around the holes is stamped or formed so as to increase the efficiency of the drum. Should a part of the drum become damaged it may be readily repaired or replaced by a new part, as the drum is 35 easily and very quickly disassembled and assembled, it being merely necessary to remove and then replace the nuts 48. It is apparent that as the wall sections and heads are made from sheet metal stamped by dies 40 and that as the parts are merely fastened together by a few screws and nuts the cost of manufacture is very low and the parts may be easily packed and cheaply transported in a "knock-down" condition and then quickly 45 assembled at their destination.

The door or closure structure of the rotating cylinder forms the subject-matter of the claims of divisional application Serial No. 614,077 filed January 22, 1923, and the 50 novel construction or formation of the metal around the vent holes 70 in the cylinder walls comprises the subject-matter of the claims of divisional application Serial No. 666,966, filed October 6, 1923.

55 While I have shown and described a cylindrical drum it is obvious that this casing or container may be of any desired shape and form and embody various features of the present invention. I have described 60 above one form of embodiment of my invention but it is to be understood that the invention is susceptible of various modifications and changes all coming within the scope and spirit of my invention, as defined 65 in the following claims.

What I claim is:

1. A drum for washing machines comprising sheet metal heads having their peripheral portions bent to provide inwardly opening grooves, a plurality of metal sections forming the wall between the heads the ends of the sections being adapted to seat in the grooves, and means connecting the heads and sections together and affording quick assembly and disassembly thereof. 70 75

2. A drum for washing machines comprising metal heads having inwardly opening grooves, metal sections forming the wall between the heads and having their ends positioned in said grooves, metal baffles between said sections, and means for connecting the heads, sections and baffles together. 80

3. A drum for washing machines comprising heads each having an inwardly opening annular groove, curved sections having their ends seated in said grooves and forming the circular wall of said drum, baffles between said sections, and means for attaching the heads directly to said baffles and thereby holding the heads, sections and 85 baffles together. 90

4. A drum for washing machines comprising metal heads having inwardly opening grooves, a plurality of metal sections forming the wall and having their ends turned outwardly and seated in said grooves, and means connecting the heads and sections together. 95

5. A drum for washing machines comprising metal heads having inwardly opening grooves, a plurality of metal sections forming the wall and having their ends turned outwardly and seated in said grooves and forming narrow channels with the heads adjacent the lines of contact, and devices connecting the heads and sections together and affording quick assembly and disassembly thereof. 100 105

6. A drum for washing machines comprising metal heads having inwardly opening annular grooves, a plurality of curved metal sections forming the circular wall, the ends of the sections being turned outwardly and seated in said grooves, baffles between the heads, and means fastening the heads directly to the baffles to connect the heads, sections, and baffles together. 110 115

7. A drum for washing machines comprising metal heads having inwardly opening annular grooves, a plurality of curved metal sections forming the circular wall, the ends of the sections being turned outwardly and seated in said grooves and forming narrow channels with the heads adjacent the lines of contact. 120 125

8. In a drum for washing machines, the combination of a plurality of sections forming the wall, and baffles between the sections and having grooves in which the edges of the sections are located. 130

9. In a drum for washing machines, the combination of a plurality of metal sections forming the wall, and metal baffles having grooves on opposite sides near their outer edges in which the edges of the sections are located and which form narrow channels between the baffles and sections adjacent the lines of contact.
10. In a drum for washing machines, the combination of a plurality of metal sections forming the wall and having curved edge portions, and baffles having curved portions complementary to and contacting with the curved edge portions of the sections.
11. In a drum for washing machines, the combination of a metal wall having a longitudinal curved edge portion, and a metal strip having a curved portion complementary to and contacting with said curved edge portion.
12. In a drum for washing machines, the combination of a metal wall having a longitudinal curved edge portion, and a metal baffle having a curved portion complementary to and contacting with said curved edge portion, the baffle and said curved edge portion of the wall providing a narrow channel adjacent the contacting surfaces thereof.
13. In a drum for washing machines, the combination of heads, a plurality of sections forming the wall, baffles between the sections and having grooves in which the edges of the sections are located, and means fastening the heads directly to the baffles to hold the heads, sections and baffles together.
14. In a drum for washing machines, the combination of heads, a plurality of sections forming the circular wall and curved adjacent their longitudinal edges, baffles having grooves curved on one side complementary to the curved portions of the sections which are located in the grooves, and means for fastening the heads to the baffles and affording quick assembly and disassembly of the heads, sections and baffles.
15. In a drum for washing machines, the combination of heads having grooves, a plurality of sections forming the wall, and strips between the sections and having grooves, the edges of the sections being located in said grooves in the heads and strips.
16. In a drum for washing machines, the combination of heads having grooves, a plurality of sections forming the wall, and strips between the sections and having grooves, the edges of the sections being located in said grooves in the heads and strips and forming narrow channels with the heads and strips adjacent the lines of contact.
17. In a drum for washing machines, the combination of heads having grooves, a plurality of sections forming the wall, baffles between the sections and having grooves, and
- means for securing the heads to the baffles, the sections being held in position by engagement of their edges in the grooves in the head and baffles.
18. In a drum for washing machines, the combination of heads having grooves, a plurality of metal sections having their ends turned outwardly and positioned in said grooves, and strips between the sections and having grooves in which the longitudinal edges of the sections are located.
19. In a drum for washing machines, the combination of heads having grooves, a plurality of metal sections having their ends turned outwardly and positioned in said grooves, strips between the sections and having grooves in which the longitudinal edges of the sections are located, and detachable means for securing the heads to the strips to afford quick assembly and disassembly of the drum the sections being held in position by engagement of their edges in the grooves in the heads and strips.
20. In a drum for washing machines the combination of heads having grooves, a plurality of metal sections having their ends turned and seated in said grooves and having their longitudinal edge portions curved, and strips having curved portions complementary to and contacting with said edge portions.
21. In a drum for washing machines, the combination of heads having grooves, a plurality of metal sections having their ends turned and seated in said grooves and having their longitudinal edge portions curved, baffles between the sections and having grooves with one side curved complementary to and contacting with said curved edge portions, and detachable means for securing the heads to the baffles and thereby afford quick assembly and disassembly of the drum.
22. In a drum for washing machines, the combination of metal heads having spaced depressions, a plurality of sections forming the wall, metal baffles having their ends seated in said depressions, and means for connecting the heads, sections and baffles together.
23. In a drum for washing machines, the combination of metal heads having spaced depressions provided with inclined sides, baffle plates having their ends in contact with the bases of said depressions and which form narrow channels with the sides of the depressions.
24. In a drum for washing machines, the combination of heads, each having a groove and spaced depressions, a plurality of sections forming the wall and having their ends seated in said grooves, baffles between the sections and having their ends seated in said depressions, and means fastening the heads to the baffles.
25. In a drum for washing machines, the combination of heads, each having a groove

- and spaced depressions, a plurality of sections forming the wall and having their ends seated in said grooves, baffles having their ends seated in said depressions and provided with grooves in which the edges of the sections are located, and detachable means for fastening the heads to the baffles and thereby afford quick assembly and disassembly of the heads, sections and baffles.
26. In a drum for washing machines, the combination of metal heads, each having a groove and spaced depressions, a plurality of metal sections forming the wall and having their ends turned and seated in said grooves and their edge portions curved, baffles having their ends seated in said depressions and provided with grooves having sides curved complementary to and contacting with said curved edge portions, and means for securing the heads to the baffles.
27. In a drum for washing machines, the combination of metal heads each having a groove with an inwardly extending annular flange adjacent the edge, a metal wall having its ends seated in said grooves and providing a door opening the portions of the flanges within said opening being rolled into the grooves.
28. In a drum for washing machines, the combination of heads, metal baffles provided with longitudinal corrugations and having ends of uniform width, with the ends of the corrugations merging with the sides of the ends to avoid sharp or rough corners, and means for securing the ends of the baffles to the said heads.
29. In a drum for washing machines, the combination of metal heads, metal baffles provided with longitudinal corrugations and having grooves on opposite sides adjacent one edge, and sections forming the wall and having their ends projecting into said grooves, and means for securing the parts together.
30. In a drum for washing machines the combination of metal heads, metal baffles between the sections and having screw threaded openings in their ends, screws in said openings and projecting through the heads, each screw having a flattened side engaging a flattened side of the opening to prevent the screw from turning, and nuts on the projecting ends of said screws.
31. In a drum for washing machines the combination of metal heads, metal baffles between the sections and having screw threaded openings in their ends, screws in said openings and projecting through the heads, each screw having a flattened side engaging a flattened side of the opening to prevent the screw from turning, nuts on the projecting ends of said screws and providing depressions in the nuts by having the screws project only partly therethrough, and solder in said depressions to prevent accidental turning of the nuts but permitting intentional detachment thereof.

ALVA J. FISHER.
